FOLDING MACHINE

Filed Oct. 30, 1929

Christian Christiansen ^{Inventor:}
By MacLeod Cahn Opland & The ^{Attorneys.}

UNITED STATES PATENT OFFICE

CHRISTIAN CHRISTIANSEN, OF LYNN, MASSACHUSETTS, ASSIGNEE TO ROTARY MACHINE COMPANY, OF LYNN, MASSACHUSETTS, A CORPORATION OF MASSACHUSETTS

FOLDING MACHINE

Application filed October 30, 1929. Serial No. 403,497.

This invention relates to folding machines for folding and pressing down the edges of various kinds of material, and is especially applicable to the type of machine shown and described in my co-pending allowed application, Serial No. 269,201, filed April 11, 1928, now Patent No. 1,743,192 dated January 14, 1930. This type of machine is particularly adapted for folding the edges of upper stock 10 of foot wear, as for instance for folding the edge of a binding strip or galloon previously stitched to the edge of the leather or other material of the upper.

An object of the present invention is to provide an improved folding machine wherein the feeding and folding are accomplished continuously as distinguished from step by step folding, and wherein means are provided in advance of the folding operation for 15 heating a relatively dry cement coating on the binding strip and thereby liquefying it sufficiently to cause it to adhere when the strip is thereafter folded and pressed down upon the body of the upper.

20 A further object of the invention is to provide a folding machine having means for feeding and folding the edge of the material or the binding strip, and in which means is provided for heating the cement on the foldable portion of the material or strip before it reaches the instrumentalities which fold the stock.

25 A further object of the invention is to provide a folding machine having a heating device which will be in continuous, even and direct contact with the cemented or gummed portion of the galloon thereby properly heating the cement.

Other objects of this invention will appear 30 in the following description and appended claims, reference being had to the accompanying drawings forming a part of this specification wherein like reference characters designate corresponding parts in the several views.

45 Fig. 1 is a side elevation, partly in section, of a folding machine embodied in my invention.

Fig. 2 is an enlarged fragmentary perspective view illustrating the invention.

50 Fig. 3 is a fragmentary plan view, partly

in section, illustrating the operation of the heating device.

Fig. 4 is a transverse section taken through the heating element and hand shield.

Before explaining in detail the present invention it is to be understood that the invention is not limited in its application to the details of construction and arrangement of parts illustrated in the accompanying drawings, since the invention is capable of other 55 embodiments and of being practised or carried out in various ways. Also it is to be understood that the phraseology or terminology employed herein is for the purpose of description and not of limitation, and it is not 60 intended to limit the invention beyond the terms of the several claims hereto appended as considered in view of the prior art and the requirements thereof.

For the purposes of illustration, I have 65 shown my present invention as applied to a machine constructed in accordance with my above mentioned application, although it will be understood that the invention may be carried out in various ways. As illustrated in the 70 drawings, the machine comprises in general a suitable base 20, to which is hinged an upper supporting frame 22, providing a housing for certain of the operating parts. Extending forwardly from the frame 22 is an overhanging arm 23 which is provided with an annular or oblique bore through which extends 75 a rotary shaft 24. Secured to the rear end of the shaft 24 is a spiral gear 25 meshing with a spiral worm 26 carried at the forward end of 80 a driving shaft 27 which is suitably journalled in the opposite side walls of the frame 22. This shaft may be driven by means of a suitable belt wheel (not shown) through the 85 medium of suitable clutch mechanism in the manner shown in my above mentioned application.

Secured to the shaft 24 is a rotatable head or upper roll 29. This rotatable head is mounted on an axis extending at an angle 90 transverse to the direction of feed. This head 29 carries a series of roller disks 30 which are mounted on short shafts (not shown) within the head 29 operated from the shaft 24. These disks 30 are preferably positive- 95

ly rotated in a direction opposite to the direction of rotation of the head 29 as indicated by the arrows. Each of the disks 30 is provided with an arcuate notch 31, and 5 the arrangement of the disks and the construction of the notches thereof are such that during operation the notches will straddle the folded edge of the material without flattening the French cord edge.

10 Beneath the rotatable head 29 is mounted a work supporting roll 32 carried by a support 33, which in turn is mounted on a flexible shaft 34, this shaft being connected with the roll 32 so as to rotate the same during the feeding and folding operations. The shaft 34 has an extension 35 carrying a worm 36 operated from the shaft 27 by a worm shaft 37.

Extending through the front wall of the 20 housing 32 is a shaft 38. This shaft carries an inverted U-shape spring arm 39. The outer end of the arm 39 is provided with an inclined guide 40, which may be termed the retainer support, within which is slidably 25 mounted a retainer bar or spindle 41 actuated by means of a spring 42. The lower end of this retainer bar 41 is bifurcated to provide outer and inner forks or arms 43 and 44. A retainer roll or disk 45 is rotatably 30 mounted within the forks on a journal pin 46. This retainer roll or disk cooperates with a projecting annular guide rib 47 formed on the lower work supporting roll 32. The support 33 carries a plow 48 which is se- 35 cured thereto by means of a screw 49, this plow having an upstanding wall 50 adapted to initially position the binding strip when the stock is placed in the machine for the folding operation.

40 The present machine is illustrated in connection with the folding of an edge of stock which, in the present instance, is shown as a piece of leather 51 having stitched along its edge at 52 a binding strip or galloon 53, 45 usually of fabric material.

In turning French cord, as illustrated in the present case, the stock is placed in the machine so that the guide rib 47 will project into the stitch line 52, and as the stock 50 is fed through the machine this guide rib follows the stitch line and guides the stock, the retainer disk 45 travelling along the edge of the material 51 so as to hold the stock on the guide rib.

55 As in my prior application the stock is simultaneously fed on and over the work supporting roll 32 by means of the overlapping disks 30 carried by the rotary head 29. These disks are located directly behind 60 the retainer roll 45 and the plow 50 and operate at an angle to the line of feed. The disks 30 are given an orbital movement by means of the rotary head 29, and also have a positive rotary movement opposite to the 65 direction of rotation of the head. The disks

are each provided with a cam face 30a commencing at the leading point 30c of the notch 31, the remainder of the disk 30b being a true circle. Each disk moves into position with the notch 31 straddling the rib 47, and as the disk continues to move it presses down the folded binding strip by means of the cam shaped edge 30a.

The disks are continuously in contact with the binding strip and on account of the fact that they continuously fold and press down the strip on an angular line as indicated by the line 54 in Fig. 3, the binding strip is partly pulled over in advance of the line of fold as shown by the portion of the binding strip indicated at 55 in Figs. 2 and 3. In practice this results in continuously dragging the binding strip across the rear face and edge of the retainer 45.

80 In commercial practice the binding strip is coated along the inner face thereof with cement or gum. The present invention enables a relatively dry or normally non-sticky cement to be used, and when the stock is fed through the machine means is provided for heating this cement sufficiently to cause it to adhere to the leather when the strip is pressed down.

85 Supported on the retainer sleeve 40 is a heat conducting member 56, preferably of aluminum. This member has a portion 56a extending downwardly along the inner side of the retainer sleeve or support and terminating at its lower end in a bearing sleeve 56b which embraces the spindle or bar 41 of the retainer disk. The retainer bar 41 has a lug 57 which works in a guide slot 58 in the bearing portion 56b. The upper end 56c of the heat conducting member 56a is cylindrical and tubular, as shown in Fig. 4, and into this tubular portion is inserted a heating element 59 of any well known electrical resistance type. This heating element is connected in circuit by means of a cable 60 carrying conductors 61 connected to a rheostat indicated diagrammatically as 62 in Fig. 4.

90 This construction enables the heating temperature of the resistance element to be controlled by shifting the lever 63 of the rheostat. The temperature of the heating device may thus be varied in accordance with requirements. The heat conducting member 56c at its upper end is partially enclosed and covered by means of a shield 64. This shield 95 is convex in shape, not only for the purpose of covering the heating element but also providing a hand hold to permit the operator to lift and lower the retainer without danger of burning her hand. The shield is provided with a projecting piece 65 which is attached by means of a screw 66 to the support 39 for the retainer.

100 The heat from the resistance element will be transmitted through the conductor 56 to the lower end of the retainer, resulting in 105

heating the retainer disk 45 to the required temperature to liquefy the cement. It will be seen therefore that the heated retainer acts on the cemented side 53b of the binding strip 5 so that the cement or gum is directly acted upon by the heat from the retainer. Moreover, in the present instance, the cemented side of the binding strip actually contacts with the retainer, and since the stock is fed 10 continuously through the machine, the binding strip is continuously in contact with the heating element. It will therefore be seen that a constant, uniform and direct heating of the binding strip at its cemented side is 15 possible by virtue of the present invention. It will also be noted that the binding strip is heated, as by means of the retainer 45, before it reaches the folding disks 30, so that the cement is properly liquefied before the strip 20 is folded and pressed down upon the leather.

I claim:

1. In a folding machine for folding a binding strip cemented at one side and stitched to the edge of a material, the combination 25 of means for folding the strip, and heat conducting means in advance of said folding means in contact with said strip at the cemented side thereof.
2. In a folding machine, the combination 30 of means for folding the edge of a material having cement along one face thereof, a member contacting on the said cemented face, heat conducting means contacting with said member, and means for feeding the material from 35 said heating means to the folding means.
3. In a folding machine for folding a binding strip cemented along one side and stitched to the edge of a material, the combination 40 of work support, means for folding the strip, a work retainer in advance of the folding means acting at the cemented side of the strip, a support for said retainer, a heat conducting member mounted on said retainer support and contacting with said retainer adjacent its 45 lower end.
4. In a folding machine for folding a binding strip cemented along one side and stitched to the edge of a material, the combination of 50 work support, means for folding the strip, a work retainer roll in advance of the folding means engaging the cemented side of the strip, and a heat conducting member contacting with said retainer for heating said roll by conduction.
5. In a folding machine, the combination of 55 means for continuously folding the edge of a piece material, a retainer including a support having a roll engaging the material, a heating element, and a heat conducting member engaging said retainer support for transmitting heat by conduction from the heating element to said retainer to cause the retainer to heat a cemented side of the material.
6. In a folding machine for folding a cemented binding strip stitched to a material,

the combination of a series of rotary disks for continuously feeding the stock and folding an edge of the strip, means for guiding the stock at the stitch line of the strip and material, and work retaining roll in advance of 70 said disks for holding the stock on the guide means, a support for said retainer, a heating element carried by said support, and a member connecting said heating element to said retainer to transfer heat by conduction. 75

In testimony whereof I affix my signature.
CHRISTIAN CHRISTIANSEN.

DISCLAIMER

1,808,158.—*Christian Christiansen*, Lynn, Mass. FOLDING MACHINE. Patent dated June 2, 1931. Disclaimer filed October 31, 1935, by the assignee, *Rotary Machine Company*.

Hereby enters this disclaimer to said claims 1 and 2 of said Letters Patent, which are in the following words, to wit:

“1. In a folding machine for folding a binding strip cemented at one side and stitched to the edge of a material, the combination of means for folding the strip, and heat conducting means in advance of said folding means in contact with said strip at the cemented side thereof.

“2. In a folding machine, the combination of means for folding the edge of a material having cement along one face thereof, a member contacting on the said cemented face, heat conducting means contacting with said member, and means for feeding the material from said heating means to the folding means.”
